UNITED STATES PATENT OFFICE.

CHARLES W. LOGAN, OF KENMORE, NEW YORK, ASSIGNOR TO MARKEL ELECTRIC PRODUCTS, INC., OF BUFFALO, NEW YORK, A CORPORATION OF NEW YORK.

DESIGN FOR A MEDALLION FOR CHANDELIERS.

Application filed April 27, 1927. Serial No. 21,751. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for a Medallion for Chandeliers, of which the following is a specification, reference being had to the accompanying drawing, forming part thereof.

In said drawing:

The figure is a front elevation of a medallion for chandeliers showing my new design.

I claim:

The ornamental design for a medallion for chandeliers, as shown.

CHARLES W. LOGAN.
